UNITED STATES PATENT OFFICE.

LESLIE R. McDONALD, OF MONTREAL, QUEBEC, CANADA.

DISPLAY APPARATUS.

Application filed July 7, 1925. Serial No. 41,908.

To all whom it may concern:

Be it known that I, LESLIE R. McDONALD, a citizen of the United States, residing at Montreal, Quebec, Canada, have invented certain new and useful Improvements in Display Apparatus, of which the following is a specification.

My invention relates to that class of display apparatuses wherein flexible placards are wound around a rotatable carrier and are allowed to unroll and drop into view position one by one; and my improvements are particularly directed to means for engaging the backs of the placards successively to lift the depending free end of the rearmost placard so as to allow it to fall forward into view position, and also to means for holding down the free end of the next placard during that operation to prevent its being displaced by adhesion to its predecessor.

My invention, which is an improvement upon the apparatus described in my Letters Patent of the United States, No. 1,539,682, dated May 26th, 1925, will be readily understood by reference to that patent and the drawings, accompanying this specification and the description herein contained.

In the drawings, Fig. 1 is a rear elevation of an apparatus showing an embodiment of my invention, the back of the case being removed and its top broken away; Fig. 2 is a side elevation, looking to the left on Fig. 1, the side of the case being removed, the lower end of the rack bar and arm broken away and the suction pump being shown in vertical section; Fig. 3 is a detail of the upper end of the suction pump and the lifting suction head, which is shortened toward its right hand end by the omission of medial portions; Fig. 4 is a similar view of the down holding suction head; Fig. 5 is a detail, taken as looking to the right on the line 5—5 of Fig. 3; and Fig. 6 is a similar detail taken as looking to the right on the line 6—6 of Fig. 4.

In all the figures similar reference numerals designate similar parts.

The case 1 is provided, as usual, with an open or glazed front 2, behind which the placards are successively exhibited, and is also provided with brackets 3, 3 supporting a frame 4 by which the operating mechanism may be carried. This operating mechanism includes a motor 5, the shaft 6 of which is provided with a worm 7, meshing

with a worm gear 8 fixed on a shaft 9, upon the inner end of which is journalled a pawl arm 10, the detent 11 of which engages with the teeth 12, 12 on the disk 13, and is normally pressed up against the same by the rotation of the shaft 9. The shaft 9 also carries an eccentric 14 upon which is mounted the feeding pawl 15 which is reciprocated by the rotation of the eccentric, so that its detent 16 will engage with the teeth 12, 12 and turn the disk 13 one step for each revolution of the shaft 9.

The further details of the construction and interrelation of this portion of the driving mechanism for the placard carrier assembly are similar to those shown in my Letters Patent No. 1,539,682, of May 26, 1925, and No. 1,477,887, of December 18th, 1923, and it is therefore unnecessary to describe them further herein. The operation of the mechanism results in turning the placard carrier forward step by step.

Mounted on and turned by the shaft 9 is a segmental gear wheel 20 meshing with a rack bar 21, sliding in a suitable guide 22 attached to the case 1, and being connected, as by arm 23 and brace 24, with the casing 25 of a pneumatic pump, the hollow piston 26 of which is carried by a base 27 attached to the bottom of the case 1.

A tube 28 extends from the top of the casing 25 to and carries a cross head 30, which is provided with a channel 31, communicating with the bore of the tube 28 and also with several flaring openings 32 in the forward side of the cross head 30.

The base of the piston shank 26 communicates, through a tube 35 with a cross head 36 having a channel 37 communicating with the bore of the tube 35 and also with several flaring openings 38 in the forward side of the cross head 36.

The normal, initial positions of the parts are those shown in the drawings, with the cross head 30 behind and against the rearmost placard and with the cross head 36 behind and against the end of the next placard.

In operation, for each step that the placard carrier is turned forward the segmental gear 20 will be given one complete revolution. This revolution lifts the rack bar 21, which carries up with it the pump casing 25, producing a partial vacuum in the pump with consequent suction in through the openings 32, 32 in the cross head 30, causing the rearmost placard 40 to adhere to

the cross head, so that the free end of the placard will be lifted as the cross head is raised, the movement being sufficiently extended to permit the placard to fall forward 5 of its own weight over the carrier, when its free end is released by the cross head.

The creation of a partial vacuum in the pump also creates a suction through the openings 38, 38 in the cross head 36 causing 10 the free end of the next placard 41 to adhere to the cross head so that the placard 41 will be held down by the cross head during the upward movement of the placard 40. This overcomes any tendency of these two 15 placards to hang together, under the influence of static electricity or otherwise.

When the segmental gear 20 has completed its arc of operative engagement with the rack bar 21, the bar will be released and 20 will slide down to its initial position, carrying the pump casing with it, eliminating the partial vacuum in the pump, and releasing the placard ends from its influence, so that the placard 40 may fall forward over 25 the carrier and the other free placard ends may be raised a step so that the end of placard 41 will register in the former position of placard 40, and another placard will be moved into the former position of placard 30 41; and the cycle of operations above described will then recur.

The influence of the partial vacuum within the pump may be modified, for instance, by making the cross heads of wood, which 35 will afford a certain amount of leakage, or by employing material more or less impervious to air such as metal or rubber.

Means, such as a regulating valve 45, may also be employed for modifying the amount 40 of suction exerted by the pump, as experience may require.

It will be understood that in illustrating the use of a segmental gear and a rack bar for reciprocating the pump I have used them 45 as types of mechanism suitable for producing such movement, and that mechanical equivalents for these elements might be substituted without departing from the spirit of my invention or the scope of my claims. 50 The same may also be said of the other elements which I have shown in the particular embodiment of my invention which I have shown and described.

It will be seen that the engagement of 55 the cross heads with the placards is of sufficient extent to avoid slipping, and is positive, so as practically to eliminate damage to the placards by wear, as there is no material friction produced by a sliding movement between the placards and the heads.

By my improvements I secure a positive, simple and efficient feeding mechanism, by the use of which placards may be lifted and thrown forward one by one while the other 60 placards in the roll will be held against dis-

arrangement by adhesion to the last one. This is peculiarly desirable with long placards which will not fall forward and unroll to their full lengths simply under their own weight. But the principle is also applicable to shorter placards when precision of operation is of much importance. 70

Having thus described my invention, what I claim and desire to secure by Letters Patent of the United States is:— 75

1. In a display apparatus, the combination of rotating means and a rotatable placard carrier, a series of flexible placards each attached by one end thereto and partially rolled thereupon with their free ends depending therefrom, and suctional means for engaging and lifting the free end of a placard. 80

2. In a display apparatus, the combination of rotating means and a rotatable placard carrier, a series of flexible placards each attached by one end thereto and partially rolled thereupon with their free ends depending therefrom, and suctional means for engaging and lifting the free end of each placard successively. 85

3. In a display apparatus, the combination of rotating means and a rotatable placard carrier, a series of flexible placards each attached by one end thereto and partially rolled thereupon with their free ends depending therefrom, and suctional means for engaging and holding down the free end of a placard. 95

4. In a display apparatus, the combination of rotating means and a rotatable placard carrier, a series of flexible placards each attached by one end thereto, and partially rolled thereupon with their free ends depending therefrom, and suctional means for engaging and holding down the free end of each placard successively. 100

5. In a display apparatus, the combination of rotating means and a rotatable placard carrier, a series of flexible placards each attached by one end thereto and partially rolled thereupon with their free ends depending therefrom, suctional means for engaging and lifting the free end of a placard and suctional means for engaging and holding down the free end of another placard. 110

6. In a display apparatus, the combination of rotating means and a rotatable placard carrier, a series of flexible placards each attached by one end thereto and partially rolled thereupon with their free ends depending therefrom, common means for producing a partial vacuum, placard raising means operated by said common means, and placard down holding means also operated by said common means. 120

7. In a display apparatus, the combination of step by step rotating means and a rotatable placard carrier, a series of flexible 130

- placards each attached by one end thereto and partially rolled thereupon with their free ends depending therefrom, means for engaging and lifting the free end of a placard and means for engaging and holding down the free end of another placard between the steps of carrier rotation.
8. In a display apparatus, the combination of step by step rotating means and a rotatable placard carrier, a series of flexible placards each attached by one end thereto and partially rolled thereupon with their free ends depending therefrom and means for engaging and holding down the free end of a placard between the steps of carrier rotation.
9. In a display apparatus, the combination of rotating means and a rotatable placard carrier, a series of flexible placards each attached by one end thereto and partially rolled thereupon with their free ends depending therefrom, and suctional means embodying a head having a plurality of suction openings therein for engaging and lifting the free end of a placard.
10. In a display apparatus, the combination of rotating means and a rotatable placard carrier, a series of flexible placards each attached by one end thereto and partially rolled thereupon with their free ends depending therefrom, and suctional means embodying a head having a plurality of suction openings therein for engaging and holding down the free end of another placard.
11. In a display apparatus, the combination of rotating means and a rotatable placard carrier, a series of flexible placards each attached by one end thereto and partially rolled thereupon with their free ends depending therefrom, suctional means, including a pneumatic suction pump, for engaging and lifting the free end of a placard.
12. In a display apparatus, the combination of rotating means and a rotatable placard carrier, a series of flexible placards each attached by one end thereto and partially rolled thereupon with their free ends depending therefrom, means for intermittently creating a partial vacuum, means rendered efficient thereby for lifting the free end of a placard, and other means rendered efficient by said partial vacuum for holding down the free end of another placard.

LESLIE R. McDONALD.
